UNITED STATES PATENT OFFICE

166,247

CLOCKCASE OR SIMILAR ARTICLE

Henry Dreyfuss, Pasadena, Calif., assignor to The
E. Ingraham Company, Bristol, Conn., a corpo-
ration of Connecticut

Application March 21, 1951, Serial No. 14,559

Term of patent 14 years

(Cl. D42—7)

To all whom it may concern:

Be it known that I, Henry Dreyfuss, a citizen of the United States, residing at Pasadena, in the county of Los Angeles and State of California, have invented a new, original, and ornamental Design for a Clockcase or Similar Article, of which the following is a specification, reference being had to the accompanying drawing, forming part thereof.

Fig. 1 is a perspective view of a clockcase or similar article as seen from the front at an angle and showing my new design;

Fig. 2 is another perspective view thereof as seen from the rear at an angle;

Fig. 3 is a side elevation thereof; and

Fig. 4 is a bottom view in plan.

I claim:

The ornamental design for a clockcase or sim-
ilar article, substantially as shown.

HENRY DREYFUSS.
